Des. 242,418
Patented Nov. 23, 1976

242,418

STRAINER

Bernard Friedman, Allentown, Pa., assignor to
Bernard Friedman

Filed Nov. 7, 1974, Ser. No. 521,907

Term of patent 14 years

Int. Cl. D7—04

U.S. Cl. D7—47

FIG. 1

FIG. 2

FIG. 3

FIG. 4

FIG. 5

FIG. 6

FIG. 7

FIG. 8

FIG. 9

FIG. 10

FIG. 11

FIG. 1 is a perspective view of a strainer showing my new design;

FIG. 2 is a front elevation (rear elevation identical);

FIG. 3 is a right side elevation;

FIG. 4 is a left side elevation;

FIG. 5 is top view;

FIG. 6 is bottom view;

FIG. 7 is a perspective view of a modified form of the strainer of FIG. 1, with snap fasteners instead of "stitched on" net basket;

FIG. 8 is a perspective view of a modified form of the strainer of FIG. 1 having a deeper net;

FIG. 9 is a top view of the modified strainer shown in FIG. 8;

FIG. 10 is a front elevation (rear elevation identical) of the modified strainer shown in FIG. 8; and

FIG. 11 is a perspective view of a modified form of the strainer of FIG. 8, which includes fixedly mounted cross members and snap fasteners.

I claim:

The ornamental design for a strainer, as shown and described.
